UNITED STATES PATENT OFFICE

ALBERT HUGUENIN, OF PARIS, FRANCE

MEANS FOR THE COOLING OF COMPRESSORS OF THE PISTON TYPE

Application filed September 18, 1928. Serial No. 306,762.

The present invention relates to the use of the method specified in the prior application No. 135,460, filed Sept. 14, 1926.

For the same general purpose of reducing the clearance to a minimum and of reducing the space employed for the mingling of a certain quantity of hot gas with the cold gas which is supplied to the cylinder by the back expansion, the device covered by the present invention may be further improved as hereinafter specified.

By way of example, the poppet valve and the slide valve are controlled by mechanical means of such nature as to provide for a long stroke of the two valves while maintaining the principle consisting in the use upon the compressor cylinder of a single discharge valve as is at present employed in the normal construction.

20 The appended drawing shows by way of example a form of construction comprising a discharge valve combined with a slide valve used for the re-admission of the cold gas which has been circulated through the intermediate cooling chamber.

Fig. 1 is a vertical section of the general device consisting of the horizontal valves, as employed for compressor cylinder having a vertical axis.

30 Fig. 2 is a horizontal section of the same.

Fig. 3 is a detail of the shaft controlling the two valves.

Fig. 4 shows the pressure-volume curve diagram of the cylinder upon which are represented the points of motion of the said valves.

Fig. 5 shows the characteristic positions of the two valves.

Fig. 6 shows the corresponding cams.

40 *a* is the interior of the compression cylinder with vertical axis; *b* is the poppet discharge valve with tapered seat, provided with its stem ending in the dash-pot *c*, said valve being applied upon its seat *d* by the spring *e*. The slide valve *f* carries at its extended end the dash-pot *g* and is held upon the same seat *d* by the spring *h*; the packing ring mounted on the cylindrical part of the valve *b* affords tightness for the annular joint between these two valves whilst the packing 45 rings *k* offer tightness for the annular joint

between the slide valve *f* and the cylindrical sleeve *l*. By means of the said sleeve and the cover *m*, the valve seat *d* is securely held in its recess. The hot gas discharged by the cylinder escapes through the space *n*, and the cold gas issuing from the intermediate cooling element circulates through the space *o* into the interior of the cylindrical slide valve *f*.

55 The same letters indicate corresponding parts in Figure 2, which also shows the shaft *p* controlling the said valve, it being in the vertical position, and also the cams *q*¹ *q*² *q*³ which are held by axial grooves *r* by means of the nut *s* engaging thread *t*. The three cams *q*¹ *q*² *q*³ (Figure 6) act—as will be further described—upon two levers *u* and *v* which act respectively upon the hollow stem of the slide valve *f* and the stem of the

50 poppet valve *b* by means of the journals *w* and *y* and the pivoting spindles *z* and *z*¹. The levers *u* and *v* carry the respective tenons *a*¹ and *a*² which are curved concentrically with the axis *b*¹ of the stationary shaft *c*¹ about 55 which are rotatable the levers *u* and *v*. The

60 said tenons *a*¹ and *a*² thus close, in all their positions, the slot *d*¹ provided in the vertical hollow track *e*¹. Its inner space is filled with 65 oil, of which only a very small part can escape, since the tenons *a*¹ and *a*² almost entirely close the only apertures *d*¹ formed in the cylinder *e*¹. The oil can be constantly renewed in the cylinder *e*¹ by a small pump (not shown).

70 The device consisting of the discharge valve and the gas-changing slide-valve is operated as follows.

75 The controlling shaft *p* rotates at the same speed as the crankshaft of the compressor in the direction of the arrow, Figure 2. The cams *q*¹ *q*² act by the tenon *a*¹ upon the lever *u* and upon the slide-valve *f*¹; and the cams *q*¹ and *q*³ act by the tenon *a*² upon the lever *v* and hence upon the valve *b*. The cam *q*¹ controls the simultaneous lift of the two valves 80 and it acts at the point *f*¹ of the curve (Figure 4), which gives the position shown at *f*¹ in Figure 5.

85 The cam *q*² releases at the dead centre, in an adjustable manner, the slide valve *f* which 90

95 offers tightness for the annular joint between these two valves whilst the packing rings *k* offer tightness for the annular joint 100

is thus closed under the action of the spring h , at the point g^1 of the curve (Figure 4), and this also gives the position shown in Figure 5. The space n for the escape of the hot gas will thus be closed, and the cold gas from o will have free access to the cylinder during the return stroke of the piston. The device is so arranged that this cold gas will enter the cylinder with the minimum loss of pressure.

At the point h^1 of the curve (Figure 4) this re-admission of cold gas is terminated by the rapid closing of the valve b by the spring e , the adjustable cam q^3 having released the tenon a^2 from the lever v . The expansion of the cold gas commences in the cylinder, and also the strong cooling which results from the same.

The cams releasing the two valves may be regulated at will upon the grooves r , so that I can in the first place adjust at the exact time desired, the closing of the hot gas and the re-admission of the cold gas, and on the other hand I can adjust the amount of this re-admission of the cold gas. The device operates with a simple mechanism and a minimum friction, and provides for long strokes of both valves with a consequent marked reduction of the loss of pressure of the gas when passing through the said valves.

Due to the fact that the slipping of the tenons a^1 and a^2 upon the cams q^1 q^2 q^3 takes place under oil so that a thin film of oil is interposed between the friction parts of these two elements, the device provides a minimum loss of energy occasioned by this inevitable friction.

The combination, covered by the present invention, of the poppet discharge valve and the slide valve for the changing of the gas, which valves rest upon a common seat d , reduces to a minimum the space in which the hot gas and the cold gas may mingle at the time of the re-admission of the cold gas, whereby the maximum efficiency of the method specified in the prior patent will be assured.

The means controlling the combination of the two valves is given solely by way of example, and other means for the same purpose may be employed.

Claims:

1. In a compressor of the piston type, the combination of a cylinder, a tapered valve seat in the wall of said cylinder, a poppet discharge valve coacting with said seat, a slide valve concentric with said poppet valve and also co-acting with said seat, a sleeve in which the said slide valve is slidable, and packing rings disposed between the said poppet valve and said slide valve, and also between the said slide valve and the said sleeve.

2. In a compressor of the piston type, the combination of a cylinder, a tapered valve seat in the wall of said cylinder, a poppet dis-

charge valve coacting with said seat, a slide valve concentric with said poppet valve and also co-acting with said seat, a sleeve in which the said slide valve is slidable, packing rings disposed between the said poppet valve and said slide valve, and also between the said slide valve and the said sleeve, and means for the simultaneous control of the said poppet valve and slide valve for opening purposes, and for the separate control of said valves for closing purposes.

3. In a compressor of the piston type, the combination of a cylinder, a tapered valve seat in the wall of said cylinder, a poppet discharge valve co-acting with said seat, a slide valve concentric with said poppet valve and also co-acting with said seat, a sleeve in which the said slide valve is slidable, packing rings disposed between the said poppet valve and said slide valve, and also between the said slide valve and the said sleeve, two pivoted arms pivoted for the respective control of the said poppet valve and slide valve, and two cams co-acting respectively with the said arms.

In testimony whereof I have hereunto affixed my signature.

ALBERT HUGUENIN.
